Letters Patent No. 1066. Dated Nov. 23, 1858.

The schedule referred to in these Letters Patent, and making part of the same.

To all whom it may concern:

Be it known that I, Samuel D. Rose, of Albany, County of Albany, State of New York, have invented a new and useful design for ornamenting Stove Castings, and I do hereby declare the following is a full and exact description of the same, reference being had to the annexed drawing, making part of this Specification.

The nature of my invention is such that it cannot be easily described in words.

The accompanying drawing (Fig. B) is a fac simile of the new design.

I do not claim as my invention any separate figure or molding.

What I claim as my invention & desire to secure by Letters Patent, is the arrangement & combination of the several figures & moldings, the whole forming together a new configuration for Stove Castings as herein described.

Witnessed,
